UNITED STATES PATENT OFFICE.

JOHN HAUENSTEIN, OF KANSAS CITY, MISSOURI.

FLASH-LIGHT SUPPORT.

Application filed May 9, 1924. Serial No. 712,138.

To all whom it may concern:

Be it known that I, JOHN HAUENSTEIN, a citizen of the United States, residing at Kansas City, in the county of Jackson and State of Missouri, have invented certain new and useful Improvements in Flash-Light Supports, of which the following is a specification.

My invention relates to flash light holders and is adapted more particularly to the small type of flash light used by motorists, railroad men and others having occasion to use a flash light. It may also be used to advantage by repairmen when working on motor cars or other machinery.

The object of the invention is to provide a flash light holder which will direct the rays of light at the most efficient angle upon the object being worked upon, said holder being made adjustable in order to throw the light at different angles as required.

With this device, it is not necessary to have an extra person to hold the light, this being accomplished by my holder, so that one person when working alone can adjust the light to the best advantage and then have his hands free to accomplish the work in question.

In the accompanying drawing which illustrates the invention:

Fig. 1 is a side view of the holder with a flash light in position thereon, said holder being adjusted to throw the light upwardly at an oblique angle as shown in full lines, and at a lesser angle as shown in dotted lines.

Fig. 2 is a plan view of the holder with the flash light removed, and the foldable leg in folded position.

Fig. 3 is an end view of the holder.

In carrying out the invention, I provide a base member 2, preferably, made of metal and having a pair of short rear legs 4 and a front leg 6 terminating in feet 7. The front leg 6 and its feet 7 are longer than the rear legs 4 and said feet extend outwardly at their lower ends to provide a firmer support and prevent the device from upsetting.

In some cases it is desired to adjust the flash light A upwardly at a greater angle than can be obtained by the legs 4 and 6, and to accomplish this I have provided a foldable leg or support 8. Said leg 8 is, preferably, made of wire and consists of side members 10, a top member 12 pivotally

mounted in the curled forward portions 14 of the base member 2 and provided with a depending stop 16 and outwardly-extending feet 18 to provide the device with a stable base not easily overturned. The intermediate portion 20 between the feet 18 is adapted to engage a spring catch 22 to hold the leg 8 when in folded position, while stop 16 is adapted to engage a spring catch 23, similar to the catch 22. The catches 22 and 23 are fixed to the underside of the base member 2.

The flash light A, which is of any ordinary or preferred form, is held in position on the device by oppositely disposed clamp members 24 secured to the base member 2 by rivets or other suitable means.

In practice, when changing a tire on a motor vehicle or other similar work where it is not necessary to adjust the light upwardly at a high angle, the device is supported upon the fixed legs 4 and 6, while the adjustable leg 8 is allowed to remain folded against the base 2, it being held in such position by the clamp 22. However, when it is desired to work under a motor vehicle or other piece of machinery where the light must be adjusted upwardly at a sharp angle, the leg 8 is brought into use by releasing it from the clasp 22 and swinging it forwardly until the stop 16 abuts the fixed leg 6, at which position the light A is adjusted upwardly at its greatest angle. The leg 8 is reliably secured in its extended position by the stop 16 engaging the spring catch 23.

From the foregoing description it is apparent that I have provided a flash light holder embodying the advantages above pointed out and while I have shown and described the preferred form of the invention, I reserve the right to make such changes in the construction, combination and arrangement of parts as properly fall within the spirit and scope of the invention as claimed.

Having thus described my invention, what I claim and desire to secure by Letters Patent, is:

1. A holder consisting of a base having a fixed leg at its forward portion to support it at an angle, a longer leg than said fixed leg pivoted at the forward portion of said base and provided with a stop so that when extended to support the base at a greater angle said stop will abut the fixed leg,

spring means for holding said stop against the fixed leg, and means on said base for supporting a flash light.

2. A holder consisting of a base having a fixed leg at its forward portion to support it at an angle, a longer leg than said fixed leg pivoted at the forward portion of said base and provided with a stop so that when extended to support the base at a 10 greater angle said stop will abut the fixed

leg, spring means for securing the pivoted leg in folded position against said base, and clamps on the base for holding a spot light.

In testimony whereof I affix my signature in the presence of two witnesses.

JOHN HAUENSTEIN.
